UNITED STATES PATENT OFFICE.

JULES L. SAGET, OF NEW ORLEANS, LOUISIANA.

FIREARM.

No. 817,937.

Specification of Letters Patent.

Patented April 17, 1906.

Application filed October 2, 1905. Serial No. 281,006.

To all whom it may concern:

Be it known that I, JULES L. SAGET, a citizen of the United States, residing at New Orleans, in the parish of Orleans and State of Louisiana, have invented new and useful Improvements in Firearms, of which the following is a specification.

My invention pertains to firearms, more particularly shoulder-firearms; and it has for 10 one of its objects to provide a firearm constructed with a view of using a subcaliber barrel or barrels and provided with means for conveniently carrying the subcaliber barrel or barrels when the same are not in use. 15 Another object of the invention is the provision of a firearm embodying a rectilinearly-movable breech-bolt and simple, strong, and reliable means whereby the breech-bolt may be quickly and easily locked in its closed position and as readily unlocked when desired. 20

Other advantageous features peculiar to my novel firearm will be fully understood from the following description when the same is considered in connection with the accompanying drawings, forming part of this specification, in which—

Figure 1 is a side elevation of the firearm constituting the present and preferred embodiment of my invention. Fig. 2 is a top 30 plan view of the same. Fig. 3 is a longitudinal vertical section of the firearm. Fig. 4 is an enlarged transverse section taken in the plane indicated by the line 4 4 of Fig. 3 looking in the direction indicated by arrow. Fig. 5 is a perspective view illustrating the breech-bolt and the parts carried thereby removed. Fig. 6 is a detail perspective view 35 illustrative of the breech-frame of the firearm. Figs. 7 and 8 are enlarged detail longitudinal vertical sections of the firearm. Figs. 9 and 40 10 are rear end elevations of the subcaliber barrels. Fig. 11 is a side elevation of the extractor which is employed on the breech-bolt when the smaller of the two subcaliber barrels is in use. Fig. 12 is a similar view of the 45 extractor used in combination with the larger of the subcaliber barrels, and Fig. 13 is a side elevation of the plug for closing the cylindrical casing in which the subcaliber barrels 50 are contained when said barrels are not in use.

Similar letters designate corresponding parts in all of the views of the drawings, referring to which—

55 A is the stock, and B the barrel, of a shotgun, which may be and preferably is of the

standard size and weight. In the rear or shoulder end of the stock a pocket a is preferably provided, said pocket being normally closed by a spring-pressed door b, hinged to the butt-plate c and being designed to hold extractors when the same are not in use, as illustrated in Fig. 3.

Fixed with respect to the stock A and barrel B in the ordinary manner or any other manner compatible with my invention is a breech-frame C. (Best shown in Fig. 6.) This breech-frame C is generally tubular in form and is provided in the upper side of its forward portion with an opening d for the insertion of cartridges and the removal of shells, and in the upper side of its rear portion with a longitudinal slot e, which extends from the opening d to the rear end of the breech-frame for a purpose presently set forth. Said breech-frame is also provided with an opening f, formed in its bottom adjacent to its rear end, and, further, with a plain lug g and a hook-shaped lug h. These lugs g and h are formed integral with or otherwise fixed to the breech-frame C, and the lug g is arranged on the upper portion of the frame at one side of the slot e and adjacent to the rear end of the frame, while the lug h extends from the side of the frame beyond the rear end thereof and is arranged at the opposite side of the slot e with reference to the lug g.

D is the breech-bolt, which is movable rectilinearly in the breech-frame C to open and close the rear end of the barrel B, and E 90 is a transversely-swinging locking member. This locking member E comprises a collar i, which loosely receives and is adapted to turn within certain limits on the rear end of the bolt D, an arm j reaching radially from said collar and having a reduced portion k and an arm l reaching laterally and forwardly from the collar at an opposite point with reference to arm j and having a kerf m in its inner side. The collar i is held against movement on the bolt D in the direction of the length of the bolt by any suitable means—such, for instance, as the pin n, fixed to the bolt and resting in a slot p of the collar. The bolt D, while free to move endwise forwardly 95 and rearwardly in the frame C, is normally held against withdrawal from said frame by a screw F, which bears in the side of the frame and has its inner end disposed in a longitudinal groove r in the bolt, Fig. 4.

It will be apparent from the foregoing that when the bolt D is moved forwardly in the

frame C until the collar *i* brings up against the rear end of said frame and the locking member E is swung toward the right the reduced portion *k* of said member will seat in the hook-shaped lug *h* of the frame, while the kerf *m* in the arm *l* of the member will receive the lug *g* of the frame. In consequence of this the breech-bolt will be strongly held in its forward position in the breech-frame in such manner that there is no liability of its being casually released. When, however, the gunner desires to open the breech, he has but to grasp the arm *j* of member E and swing the said arm upwardly, when the member E will be disengaged from the breech-frame and may be used as a means to move the breech-bolt rearwardly and forwardly. G is a sear suitably mounted in the stock A and connected with a trigger H, and I is a firing-pin mounted in guides in the bolt D. The said firing-pin is surrounded by a spring *s*, which is interposed between its enlargement *t* and one of the guides in the bolt D and tends to press the pin forwardly. It is also provided at an intermediate point of its length with a beveled lug *u* and at its rear end with an enlargement *v*. When the breech-bolt is moved rearwardly, the firing-pin will move with it, the beveled lug *u* riding over the sear G. On the subsequent forward movement of the breech-bolt, however, the lug *u* will bring up against the sear G, with the result that when the breech-bolt is locked to the breech-frame the firing-pin will be cocked. J is an extractor detachably connected, preferably by a screw *w*, to the upper side of the breech-bolt D. This extractor extends in advance of the forward end of the bolt D and is provided with a beveled head *x*, designed to rest in a notch *y* in the forward end of the breech-frame C and engage the rim of a cartridge, so that when the breech-bolt is moved rearwardly the cartridge will be drawn out of the barrel B and into the breech-frame, from whence it may be readily removed. K is a spring-bar arranged alongside of and connected at its rear end to the breech-frame C and having a lateral projection *z* at its forward end disposed in an aperture *a'* of said frame, and L is a screw-bearing in the bar K and against the outer side of the frame C. When the screw L is turned inwardly, the forward end of the bar K and the projection *z* will be drawn outwardly, and hence a subcaliber barrel may be shoved forwardly into the barrel B and past the projection *z*. When, however, the bar K and the projections *z* rest in their normal positions, the latter will obviously hold the subcaliber barrel against casual rearward movement in the barrel B. Fixed with respect to the stock A and the barrel B and arranged longitudinally below the latter is a cylindrical casing M open at its

forward end. This casing is normally closed by a plug M', having a knurled edge, and when desired the said plug may be equipped with a screw-driver *b'*, which may be used to loosen and tighten the screw *w* for connecting the extractor J.

N is a comparatively large subcaliber barrel. P is a small subcaliber barrel, and Q is a collar designed to be mounted on the forward end of the subcaliber barrel P when the latter is placed in the barrel B, with a view of holding said forward end against lateral deflection. These parts are designed when not in use to be arranged in the casing M, as shown in Fig. 3—that is to say, with the barrel P in the barrel N and the collar Q between the ends of said barrels N and P and the plug M'. The subcaliber barrels N and P are respectively provided at their rear ends with a rim *c'*, having a notch *d'* to receive the head of an extractor and a recess *e'* to receive the projection *z* on the bar K.

R and S are extractors designed to be used in combination with the subcaliber barrels N and P, respectively. These extractors are similar in construction, except that the head of the extractor S is longer than that of the extractor R. When not in use, the said extractors are designed to be carried in the pocket of the stock, as shown in Fig. 3.

When it is desired to use one of the subcaliber barrels in my improved firearm, the screw F is loosened, the breech-bolt D is removed from the breech-frame C, and the screw L is turned inwardly to move the projection *z* on bar K outwardly. With this done the desired subcaliber barrel is moved from the casing M and removed forwardly through the breech-frame C and the barrel B until its rim abuts against the rear end of the barrel B, when the screw L is turned outwardly to move the bar K and the projection *z* inwardly, so as to seat the latter in the recess in the rim of the subcaliber barrel, and thereby secure said barrel against casual movement relative to the barrel A. The breech-bolt D is then replaced and secured in the breech-frame C, and the extractor R or S, corresponding to the subcaliber barrel put in use, is substituted for the extractor J.

When the firearm is changed, as described in the foregoing, it will be apparent that it constitutes either a small-bore shotgun or a rifle.

To restore the firearm to its original condition shown in Figs. 1 to 3, it is simply necessary to remove the subcaliber barrel from the barrel B and place said subcaliber barrel in the casing M.

It will be gathered from the foregoing that the owner of my novel firearm is enabled while in the field and without the employment of skilled labor to readily convert the firearm from an ordinary shotgun into a small-bore shotgun or rifle, or vice versa, also

that the firearm embodies no delicate parts, and is therefore well adapted to withstand the usage to which firearms are ordinarily subjected.

5 By reference to Figs. 7 and 9 of the drawings it will be observed that the smaller subcaliber barrel P is arranged off the center of its rear enlargement a⁷ and the collar Q. By virtue of this when the subcaliber barrel is placed in the barrel B and a small rim-fire cartridge is placed in the subcaliber barrel the firing-pin I when impelled forward will strike the rim of the cartridge and explode the same.

15 When the barrel B is employed alone or the larger subcaliber barrel N is placed in said barrel B, it will be observed that the firing-pin I will strike the center of the cartridge placed in said barrel B or N. From this it follows that without change in the firing mechanism my novel firearm is adapted to 20 explode either center-fire or rim-fire cartridges.

M⁷ is a shell-ejector. This ejector comprises a plunger m⁷, movable upwardly and downwardly in the stock and extending into the lower portion of the breech-frame, and a spring m⁸, carrying the plunger and connected at its end remote from the same to the under side of the stock, as best shown in Fig. 7. The upper end of the plunger m⁷ is beveled at the rear, as shown, and hence it will be seen that when the breech-bolt is moved forwardly it will ride over and depress the plunger, and thereby place the spring m⁸ under tension. When, on the other hand, the breech-bolt is moved rearwardly and the extractor J brings a cartridge-shell with it, the rim of the shell will assume a position above the shoulder of 35 the plunger, so that when the plunger is released by the breech-bolt and impelled upwardly by the spring m⁸ it will operate to forcibly throw the shell out of the breech-frame through the opening in the top thereof.

45 Having described my invention, what I claim, and desire to secure by Letters Patent, is—

1. In a firearm, the combination of a stock, a barrel, a breech-frame fixed with respect to the stock and barrel and open at its rear end and having a plain lug at one side adjacent to its rear end and also having a hook-shaped lug arranged at its opposite side and extending beyond said rear end, a sear mounted in the stock and extending into the breech-frame, a trigger also mounted in the stock and connected with the sear, a breech-bolt movable rectilinearly in the breech-frame, a transversely-swinging locking member held on the breech-bolt against movement in the direction of the length thereof and having a radial arm and a lateral arm provided with a kerf; the said radial arm being arranged when the breech-bolt is in its closed position, to seat in the hook-shaped lug, and the kerf 55 to seat in the hook-shaped lug, and the kerf 60 on the breech-bolt against movement in the direction of the length thereof and having a radial arm and a lateral arm provided with a kerf; the said radial arm being arranged when the breech-bolt is in its closed position, to seat in the hook-shaped lug, and the kerf 65 to seat in the hook-shaped lug, and the kerf

in the lateral arm being arranged to receive the plain lug, and a spring-pressed firing-pin carried by the breech-bolt and having a beveled lug arranged to be engaged by the sear.

2. In a firearm, the combination of a breech-frame open at its rear end and having a plain lug at one side adjacent to its rear end and also having a hook-shaped lug arranged at its opposite side and extending beyond said rear end, a breech-bolt movable rectilinearly in said frame, and a transversely-swinging locking member held on the breech-bolt against movement in the direction of the length thereof and having a radial arm and a lateral arm provided with a kerf; the said radial arm being arranged, when the breech-bolt is in its closed position, to seat in the hook-shaped lug, and the kerf in the lateral arm being arranged to receive the plain lug.

3. In a firearm, the combination of a breech-frame open at its rear end and having an opening in the upper side of its forward portion and a longitudinal slot extending from said opening to its rear end and also having a plain lug at one side adjacent to its rear end and a hook-shaped lug arranged at its opposite side and extending beyond said rear end, a breech-bolt movable rectilinearly in said frame, an extractor arranged on said breech-bolt and adapted to be withdrawn through the longitudinal slot in the breech-frame, and a transversely-swinging locking member held on the breech-bolt against movement in the direction of the length thereof and having a radial arm and a lateral arm provided with a kerf; the said radial arm being arranged, when the breech-bolt is in its closed position, to seat in the hook-shaped lug, and the kerf in the lateral arm being arranged to receive the plain lug.

4. In a firearm, the combination of a stock, a barrel, a breech-frame fixed with respect to the stock and barrel and open at its rear end and having a plain lug at one side adjacent to its rear end and also having a hook-shaped lug arranged at its opposite side and extending beyond said rear end, a sear mounted in the stock and extending into the breech-frame, a trigger also mounted in the stock and connected with the sear, a breech-bolt movable rectilinearly in the breech-frame, a transversely-swinging locking member held on the breech-bolt against movement in the direction of the length thereof and having a radial arm and a lateral arm provided with a kerf; the said radial arm being arranged, when the breech-bolt is in its closed position, to seat in the hook-shaped lug, and the kerf in the lateral arm being arranged to receive the plain lug, a spring-pressed firing-pin carried by the breech-bolt and having a beveled lug arranged to be engaged by the sear, an extractor carried by the breech-bolt and movable in the breech-frame, and an ejector comprising a plunger extending into the

breech-frame, and a spring for impelling said plunger when the same is released by the breech-bolt.

5. In a firearm, the combination of a breech-frame open at its rear end and having a plain lug at one side and a hook-shaped lug at its opposite side, a breech-bolt movable rectilinearly in the breech-frame, a transversely-swinging locking member comprising 10 a collar loosely surrounding the rear portion of the breech-bolt and having a slot, an arm extending radially from said collar and adapted to engage the hook-shaped lug, and an arm reaching laterally forward from the 15 collar and having a kerf to receive the plain lug, and a pin fixed to the breech-bolt and disposed in the slot of the collar.

6. In a firearm, the combination of a barrel, a breech-frame fixed with respect to the 20 barrel and open at its rear end and having an opening in its forward portion and a slot extending rearwardly from said opening to its rear end, a breech-bolt movable rectilinearly

in the breech-frame and adapted to be withdrawn through the rear end thereof, an extractor carried by the breech-bolt and arranged to be withdrawn through the slot of the breech-frame, means removably securing the breech-bolt in the breech-frame, a subcaliber barrel adapted when the breech-bolt 25 is removed to be introduced through the breech-frame and into the barrel, said subcaliber barrel having a rim at its rear end provided with a notch and a recess, and an adjustable bar connected to the breech-frame 30 and having an inwardly-directed projection arranged to enter the recess in the rim of the subcaliber barrel.

35 In testimony whereof I have hereunto set my hand in presence of two subscribing witnesses.

JULES L. SAGET.
